[57] **CLAIM**

The ornamental design for a foot pedal pad for automotive vehicles, as shown and described.

DESCRIPTION

FIG. 1 is a perspective view of a foot pedal pad for automotive vehicles showing my new design;

FIG. 2 is a side elevation view thereof to an enlarged scale;

FIG. 3 is a top plan view thereof to an enlarged scale;

FIG. 4 is a bottom plan view thereof to an enlarged scale; and

FIG. 5 is a front elevation view thereof to an enlarged scale, it being understood that the rear is a mirror image of the front shown.

FIG.1
